WATER CIRCULATING PUMP

Filed Oct. 17, 1923

INVENTOR
William J. Campbell,
BY
Arthur M. Hood.
ATTORNEY

UNITED STATES PATENT OFFICE.

WILLIAM J. CAMPBELL, OF INDIANAPOLIS, INDIANA, ASSIGNOR TO CLIMAX MACHINERY COMPANY, OF INDIANAPOLIS, INDIANA, A CORPORATION OF INDIANA.

WATER-CIRCULATING PUMP.

Application filed October 17, 1923. Serial No. 669,032.

To all whom it may concern:

Be it known that I, WILLIAM J. CAMPBELL, a citizen of the United States, residing at Indianapolis, in the county of Marion and 5 State of Indiana, have invented a new and useful Water-Circulating Pump, of which the following is a specification.

The object of my invention is to produce a cheap and efficient pump especially designed for insertion in the water-circulating 10 system of internal combustion engines of automobiles.

The accompanying drawings illustrate my invention.

Fig. 1 is a vertical section of a pump embodying my invention, with adjacent portions of the engine of a well known make of automobiles, and Fig. 2 is a plan of the parts shown in Fig. 1.

In the drawings 10 indicates a fitting formed for attachment at the water inlet opening of the water jacket of engine 11. Fitting 10 is provided with a water passage 12 having a circular receiving end to which 20 is secured a pump body 14 having a pump chamber 15 which, at its discharge end, registers with the receiving end of passage 12.

Body 14 is provided with an extension 16 arranged axially of pump chamber 15 and 30 provided at its ends with shaft bearings 17, 17 separated by an oil chamber 18, and at its outer end provided with a packing gland 19.

Journalled in bearings 17 is an impeller shaft 20 the outer end of which carries a pulley 21. Secured to the inner end of shaft 20 35 is a screw-type impeller 22 lying within chamber 15.

Leading into the receiving end of chamber 15, preferably at an acute angle to the axis 40 thereof, is an inlet passage 23 adapted to be connected, by any suitable connection, such as a flexible hose, with the lower part of a radiator (not shown).

As there is always a possibility that the 45 belt driving pulley 21 may tend to thrust the shaft inwardly, I resist such thrust by a bridge bar 25 arranged across passage 12 and body 14 and having a central portion

26 against which the inner end of shaft 20 abuts. 50

Bar 25 and part 26 are preferably given stream-line cross-sections so as to offer minimum resistance to water flow.

It is important, in connection with an impeller of the type shown, that the oncoming 55 water stream be prevented from whirling, and to accomplish this result, I carry the inlet passage 23 along each side of the rear bearing 17, and provide diametrically arranged, stream-line section, baffle ribs 60 23', 23'.

By bringing the inlet passage 23 into the impeller chamber substantially in the line of propulsion produced by the screw blades 65 of the impeller, I reduce to a minimum the resistance to flow through the pump.

The side pull of the belt may be resisted by a set-screw 30 threaded with a boss 31 on extension 16 and adapted to be adjusted 70 so as to contact with the body of engine 11.

Oil or grease may be delivered to the oil chamber 18 through a cup 32.

It will be noted that the construction is such that the impeller chamber is self draining without the need of special drainage 75 passages.

I claim as my invention:

A water circulating pump for engines comprising an elbow fitting having one face thereof finished to fit the water inlet of an engine jacket and provided with means for securing said fitting to the engine jacket, said fitting having a curved water passage-way therethrough and an outlet opening at right angles to the inlet opening, a thrust bar arranged across said inlet opening, and a pump body secured to and supported by said fitting and forming a closure for the receiving opening thereof and having an impeller chamber, an axial shaft bearing extension of said pump body having spaced apart bearings therein, a shaft journaled in said bearings and extending through said bearing extension having one end in thrust engagement with said thrust bar, a screw 95 type impeller carried by the inner end of

said shaft and arranged within said impeller chamber, said impeller chamber having a water inlet substantially axially thereto and extending into a diverging extension of said shaft bearing extension and baffle ribs arranged across the inlet passage closely adjacent the receiving end of the impeller, said securing means for the elbow fitting

constituting the sole mounting members for the circulating pump.

10

In witness whereof, I, WILLIAM J. CAMPBELL, have hereunto set my hand at Indianapolis, Indiana, this 13th day of October, A. D. one thousand nine hundred and twenty-three.

WILLIAM J. CAMPBELL.
